UNITED STATES PATENT OFFICE.

PETER LEPAK, OF PITTSBURGH, PENNSYLVANIA.

ARTICLE-SUPPORTING STAND.

1,226,543.

Specification of Letters Patent. Patented May 15, 1917.

Application filed August 13, 1915. Serial No. 45,384.

To all whom it may concern:

Be it known that I, PETER LEPAK, a citizen of the United States, residing at Pittsburgh, in the county of Allegheny and State of Pennsylvania, have invented certain new and useful Improvements in Article-Supporting Stands; and I do hereby declare the following to be a full, clear, and exact description of the invention, such as will enable others skilled in the art to which it appertains to make and use the same.

My invention relates to new and useful improvements in article supporting stands and my object is to provide a frame for supporting a comb and brush, said frame having a mirror attached thereto.

And a further object is to provide receptacles in connection with the stand for supporting matches, hair pins, hat pins, and the like.

Other objects and advantages will be hereinafter set forth and more particularly pointed out in the accompanying specification.

25 In the accompanying drawings which are made a part of this application,

Figure 1 is a front elevation of the stand complete, and

Fig. 2 is a top plan view thereof.

30 Fig. 3 is a detail fragmentary perspective view showing how the ends of the band forming the frame are given a quarter turn to form a supporting standard.

Referring to the drawings in which similar reference numerals designate corresponding parts throughout the several views, 1 indicates the frame of the stand which is preferably constructed of a flat piece of metal and bent to rectangular shape, the 35 ends of the strips of metal forming the frame being given a quarter turn and extended upwardly to form a standard 2, the strips of metal above said standard being separated and formed into a frame member 3 into which is introduced a mirror 4, said

50 mirror being held within the frame member in any suitable manner as by means of clips

5. The extreme ends 6 of the strips of metal forming the frame are brought together

55 above the mirror and securely engaged with each other by extending a rivet 7, or the like, through said ends, one of the ends being

formed into a hanger 8 so that the stand can be engaged with a nail or hook and suspended from a wall or other convenient point.

The strips of metal forming the stand 2 are parallel with each other and are formed into a rigid structure by introducing rivets 9 and 10 transversely through the sections adjacent their upper and lower ends. By forming the parts described in this manner, they can be very cheaply constructed as they are all formed from a single strip of material. The frame 1 is provided with supporting legs 11 adjacent its ends, said legs extending a distance above, and below the frame, the lower ends of the legs forming a support, while the upper ends thereof serve as a guard for articles that 65 may be placed upon the frame. Extending transversely across the frame 1 and secured to the side members thereof are a plurality of wires 12 which form a base or bottom in the frame for the reception of a comb and 70 brush, or other similar articles.

Attached at any suitable point to the frame 1, preferably to the front side piece thereof, are cup-shape receptacles 13 which are designed to receive various small articles, 80 such as hair pins, matches and the like, though it will be clearly understood that said receptacles may be placed at any suitable point on the frame as may be desired.

Attached at a suitable point to the stand 2 is a tray 14 semicircular in cross section for the reception of hat pins, pencils, or similar articles, said tray being placed a sufficient distance above the frame 1 as not to interfere with the removal of the articles 90 resting upon the frame. The stand is constructed entirely of light metal with the exception of the mirror and can therefore be very cheaply produced, while at the same time it will be extremely strong and durable 95 and by providing the hanger above the mirror and the supporting legs for the lower frame, the stand can be suspended from a wall or other suitable point or rest upon a dressing table or the like as is most convenient for the user.

Having thus fully described my invention what I claim as new and desire to secure by Letters Patent of the United States, is:

An article supporting device of the class 100 described formed from a single flat band of metal bent into rectangular shape to form a frame, wires extending transversely of the frame, the ends of said band being given a quarter turn and extended upwardly in parallel abutting relation to provide a standard, 110 securing means extending through said

standard, the upper ends of those portions of the band forming the standard diverging for a distance and then converging to form a mirror supporting frame, thence extending vertically in abutting relation, and a retaining screw extending through said abutting portions and serving to draw the upper end portions of the mirror supporting frame together to clamp and hold the mirror in place, one of said upper terminal ends being

given a quarter twist and provided with an aperture whereby the device may be hung from a suitable support.

In testimony whereof I have signed my name to this specification in the presence of two subscribing witnesses,

PETER LEPAK.
